US00D949132S

(12) **United States Design Patent** (10) **Patent No.:** **US D949,132 S**
Cong et al. (45) **Date of Patent:** **** Apr. 19, 2022**

(54) **PLANAR ANTENNA**

(71) Applicant: **Galvani Bioelectronics Limited**,
 Hertfordshire (GB)

(72) Inventors: **Peng Cong**, Burlingame, CA (US);
Damiano Patron, South San Francisco,
 CA (US); **Stephen O'Driscoll**, South
 San Francisco, CA (US)

(73) Assignee: **Galvani Bioelectronics Limited**,
 Hertfordshire (GB)

(**) Term: **15 Years**

(21) Appl. No.: **29/788,078**

(22) Filed: **Mar. 9, 2021**

(57) **CLAIM**

The ornamental design for planar antenna, as shown and described.

DESCRIPTION

FIG. 1 is a perspective view of a planar antenna showing the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines illustrate environment and portions of the antenna that form no part of the claimed design.

1 Claim, 5 Drawing Sheets
